OIL DISTILLATION APPARATUS

Arthur E. Pew, Jr., Bryn Mawr, Pa., assignor
to Sun Oil Company, Philadelphia, Pa., a cor-
poration of New Jersey

Original application April 4, 1929, Serial No.
352,392. Divided and this application August
6, 1931. Serial No. 555,391

6 Claims. (Cl. 196—119)

In a patent issued to me September 27, 1932, No. 1,879,948, of which this application is a division, I have set forth a process and apparatus for producing lubricating oil distillates of different boiling points wherein the heat required for effecting distillation, at least of a number of the higher boiling fractions, is supplied by the condensation of mercury vapor generated in a plurality of mercury boilers. The construction and arrangement whereby these boilers are connected with a series of stills are not therein claimed and form the subject matter of this application.

The present invention may be fully disclosed by a description of that part of the apparatus which is in operative relation with the mercury boilers and which is shown in diagram in the single figure of the drawing.

In the said apparatus gasoline, kerosene, gas oil and lighter lubricating oil fractions may be distilled in an apparatus forming no part of the present invention. For example, the lubricating oil fractions distilled in such apparatus may comprehend lubricating oils of 100, 200, 300 and 500 at 100° F. viscosity.

The residual oil from these preliminary distillations may be, however, so far as concerns the present invention, oil from which any desired fractions have been distilled. It is pumped through a line 40 and through a pipe coil 41 in a heating chamber 70. The heating medium in this chamber is, preferably, mercury vapor, but other heating media may be substituted, particularly substances such, possibly, as diphenyl oxide, benzo phenone, sulfur, or perhaps a suitable metal alloy, as may be found to possess those characteristics of mercury vapor that make it especially advantageous in the distillation of the higher boiling lubricating oils. It will be understood, therefore, that, hereinafter, when "mercury boilers" are referred to, the term is intended to include boilers adapted to vaporize materials which are in a broad sense, equivalent to mercury.

In chamber 70 the mercury vapor condenses and imparts its latent heat to the oil flowing through coil 41. The mercury vapor is generated in a mercury boiler 71 from which extends a mercury vapor pipe line 72 to chamber 70. Pipe 72 is equipped with a valve 73, by means of which the rate of flow of the mercury vapor into chamber 70, and thereby the pressure and temperature of condensation within the same and the heat to which the oil is subjected may be accurately regulated. This temperature of condensation should be such that there will be a comparatively low

temperature difference between the oil flowing through coil 41 and the surrounding mercury vapor as measured by the logarithmic mean temperature difference at the inlet and the outlet of the coil.

Extending from chamber 70 is a mercury condensate return, which comprises a clean out cup 74, goose-neck 75, pipe 76 and chamber 77 communicating with boiler 71. The connections shown are adapted not only to allow mercury condensate to return to boiler 71, but also to provide balancing columns of liquid mercury (in goose-neck 75) to take care of pressure differences between boiler 71 and chamber 70.

In coil 41 the oil is heated to the desired temperature, say 625° F., and sufficient latent heat is applied to vaporize the desired fraction within the coil; or, alternatively, the pressure within the coil may be so fixed as to prevent vaporization within the coil and permit the conversion of sensible heat to latent heat in tower 42, as hereinafter more fully described. Assuming that the vaporization is effected within the coil, the oil thus heated and partly vaporized enters tower 42, which may have any known efficient internal construction. In this tower the vapors are condensed. A small proportion of stink oil, comprising also incondensable gases, escapes through line 43 and condenser 44 into receiving tank 45, whence the condensed stink oil may be pumped to storage. The main part of the condensed product flows through line 46 into a deodorizer 47, which is subjected to a high vacuum and in which the remainder of the odor-producing gases are removed, the purified oil flowing through a cooler 48 into a tank 49, from which it is pumped to storage.

The absolute pressure in tower 42 is maintained at such a point as will enable the vaporization, in coil 41, of the desired proportion of oil at as low a temperature as practicable. This high vacuum may be established and maintained through vacuum lines 50, 50.

The oil not vaporized in tower 42 and not escaping through line 46 flows through another coil 51 in another mercury vapor condensing chamber 80. Herein the oil is heated to a somewhat higher temperature than in coil 41, resulting in another partial vaporization, and flows into a tower 52, wherein the vaporized fraction is condensed: the operation being the same as in tower 42, but with the production of a higher boiling range oil distillate.

I have shown still another mercury vapor condensing chamber 89, coil 61 and tower 62, in

series with the fractional distillation units 70, 41, 42 and 80, 51, 52, above described, for the production of a still higher boiling range distillate. There may be a variable number of these units, 5 dependent on the fineness of the cuts desired, and dependent also on the proportion of the distillates which it is desired to produce by the use of mercury vapor as a heating medium as compared with the proportion of relatively light distillates 10 which it is desired to obtain in the preliminary distillation hereinbefore referred to, forming no part of the present invention. Other factors also will govern the design of the plant. With the use of a considerable number of units, the temperature elevations in each unit will be reduced, 15 with the resultant advantage that the oil will be subjected to the action of the heating medium for very short periods of time.

Any number of boilers may be used. In the 20 drawing is shown two boilers, 71 and 81, with mercury vapor outflow lines 72 and 82 respectively and mercury condensate return lines 76 and 86 respectively. Boiler 71 is shown as connecting with oil heater 70 and boiler 81 with oil heater 25 89, while each boiler is connectible with oil heater 80 through branch mercury vapor inlet pipes 720 and 820 respectively and mercury condensate return line 78, which latter may be connected with either line 76 or line 86 through one of the 30 goose-necks 84. Mercury vapor lines 72 and 82 may be cross-connected by means of pipe 700. Chambers 77 of the mercury condensate returns to the two boilers may be cross-connected by means of pipe 110. Valves 111 are positioned in 35 the short pipes connecting chambers 77 with their respective boilers and a valve 112 is positioned in the cross-connecting pipe 110. Thereby, either boiler may be connected, and the other disconnected, with all the oil heating chambers.

40 The described arrangement of boilers may be varied as desired. The use of two boilers is desirable, since it allows the generation of mercury vapor at pressures more nearly approximating the pressures desired in the oil heaters connected therewith and it also provides against a shut down in case one boiler should be disabled. One boiler, however, is all that is required, in view of the capacity to independently regulate the pressures in the several chambers by means of the throttle valve 73, 83 or 88 and the balanced mercury columns in the goose-necks 75, 84 and 85.

45 While, as hereinbefore described, the partial vaporization of the oil flowing through coils 41, 51 and 61 occurs in the coils themselves, it may be 55 preferable to prevent vaporization within the coils, thereby preventing any direct transfer of heat to the vapors. This can be effected by means of pressure regulating valves 101, 102 and 103 on the 60 pipes leading from the coils to the towers 42, 52 and 62. When this variation is adopted, it is necessary to heat the oil in each coil to a somewhat higher temperature than would be otherwise required to permit the conversion of sensible heat to latent heat in the succeeding tower. Such 65 variation of the process is also of advantage in keeping the tubes clean, since the entire contents are a liquid and therefore able to carry more suspended matter. With certain crudes, however, the higher temperatures necessitated by the maintenance of the oil would tend to cause cracking or decomposition. This may be largely or wholly overcome, however, by using a multiplicity of units. It is, of course, possible to apply pressure regulating valves only to the first one or more units 70 of the series, since the required temperature to

which the oil must be raised therein is comparatively low. In the absence of pressure control regulators, the oil in each coil will be under a vacuum but little lower than that in the tower, 42, 52 or 62, just beyond the coil.

80 It is desirable that provision be made to shut the boilers down if it becomes necessary to shut off the flow of mercury to the oil heaters. Should the main valves 94 on lines 72 and 82 be closed, the safety valves 95 would open and the mercury would rise and condense in condenser 96, flowing back, through the seals 97 into lines 76 and 86 and thence into the boiler.

85 It should be understood that the present invention is not dependent on the use of any particular type of still. The stills above described merely illustrate one type of still with which the mercury boilers may be connected as herein described; but the same connections may be made to stills of many different specific constructions.

90 What I claim and desire to protect by Letters Patent is:

1. The combination with a plurality of stills arranged in series, of two mercury boilers, a mercury vapor flow pipe from one boiler communicating with one or more stills and a mercury vapor flow pipe from the other boiler communicating with one or more other stills, and a cross-connecting mercury vapor flow pipe connecting the mercury vapor flow pipes from the two 105 boilers.

2. The combination with a plurality of stills arranged in series, of two mercury boilers, pipe connections providing for a flow of mercury vapor from one boiler to one or more stills and for the return of condensed mercury to the boiler, pipe connections providing for a flow of mercury vapor from the other boiler to one or more other stills and for the return of condensed mercury to the boiler, and valve controlled cross-connecting pipes permitting flow of mercury vapor from either boiler to all the stills and for permitting return of condensed mercury from all the stills to either boiler.

3. The combination with three stills arranged 120 in series, of two mercury boilers, a mercury vapor flow pipe from one boiler to one end still and a mercury vapor flow pipe from the other boiler to the other end still, a mercury vapor flow pipe to the middle still, and means to connect the mercury vapor flow pipe to the middle still with the mercury vapor flow pipe from either mercury boiler.

4. The combination with three stills arranged 130 in series, of two mercury boilers, pipe connections providing for a flow of mercury vapor from one boiler to one end still and for the return of condensed mercury to the boiler, pipe connections providing for a flow of mercury vapor from the other boiler to the other end still and for the 135 return of condensed mercury to the boiler, pipe connections providing for flow of mercury vapor to the middle still and for return of condensed mercury therefrom, and means to connect the flow pipes to and from the middle still with the corresponding flow pipes to and from either of the other stills.

5. The combination with a plurality of stills arranged in series, of two mercury boilers, a mercury vapor flow pipe from one boiler communicating with one still or combination of stills and a mercury vapor flow pipe from the other boiler communicating with another still or combination of stills, and a cross-connecting mercury vapor 145
